(57) **CLAIM**

The ornamental design for a handle of handsaw, as shown and described.

DESCRIPTION

FIG. 1 is a front view of the handle of handsaw of the present invention;

FIG. 2 is a top plan view thereof;

FIG. 3 is a back view thereof;

FIG. 4 is a bottom plan view thereof;

FIG. 5 is a right side view thereof;

FIG. 6 is a left side view thereof;

FIG. 7 is a perspective view thereof; and,

FIG. 8 is a front view thereof, wherein the broken line showing of the blade is for illustrative purposes only and forms no part of the claimed design.
